(57) **CLAIM**

The ornamental design for a combined vacuum cleaner and blow dryer for pet grooming, as shown and described.

DESCRIPTION

FIG. 1 is a perspective view of a combined vacuum cleaner and blow dryer for pet grooming showing my new design; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; and, FIG. 8 is a bottom plan view thereof.

The dash-dash broken lines in the drawings depict portions of the combined vacuum cleaner and blow dryer for pet grooming that form no part of the claimed design.

The dot-dash broken lines represent boundaries of the enlarged portions and form no part of the claimed design.
